SPRING CUSHION HAVING THE LOAD SUPPORTING PORTION REINFORCED BY FABRIC

Byron C. Gould, Detroit, Mich., assignor to The Murray Corporation of America, Detroit, Mich., a corporation of Delaware

Application April 25, 1949, Serial No. 89,476

3 Claims. (Cl. 155—179)

1

This invention relates to spring cushions, and particularly a spring cushion having a load-supporting portion made from zigzag spring strips which are interconnected by fabric strips inwardly from the front and rear edges of the cushion, and to the method of applying the fabric material to the spring strips.

The cushion of the present invention is constructed from spring strips of the zigzag type made of wire bent back and forth to provide adjacent oppositely disposed loops joined by straight portions. The spring strips are preferably arched along their longitudinal dimension to provide a set on a curve of short radius to resist downward deflection when the spring strips are mounted in a frame with the ends extended to provide a seating or load-carrying portion disposed on an arc of large radius. After a plurality of the spring strips are mounted in a frame, it has been the practice heretofore to interconnect the adjacent spring strips at spaced points with wire clips so as to distribute the load over the load-supporting portion of the cushion. Difficulty was experienced in various assemblies when attempting to produce a proper and desirable contour to the seating area of the spring strips. Various attempts were made to supplement the load-carrying qualities of the spring strips by braces, additional spring supports and the like to produce a proper contour.

These difficulties were overcome when practicing the present invention which embodies the application of a layer of fabric material at the central portion of the seating area of the spring strips. A layer of the fabric material was applied to both sides of the assembled seating portion of the cushion and joined together in a suitable manner, preferably by an adhesive material. After the spring cushion was constructed, a layer of the fabric material was laid upon a flat or contoured surface and the cushion turned over to have the load-supporting portion rest upon the material. A second strip was placed upon the inside of the spring strips aligned with the first layer of material with an adhesive disposed therebetween. A pad, roller, or other suitable implement was then applied to the material for bonding the two layers of material together between the spring strips and about the convolutions thereof. Substantial rigidity was provided to the spring strip at the points in which the fabric layer was applied, and a unison action was produced to the plurality of strips when a load was applied at various points of the seating.

Accordingly, the main objects of this invention

are to utilize a fabric material at the central load-supporting portion of a seating area constructed from zigzag spring strips for tensioning the area and strip and controlling the contour thereof when loaded; to form a spring cushion from zigzag spring strips and provide a tension to and interconnection for the strips by layers of fabric material applied to both sides of the seating area of the cushion at the central load-supporting portion thereof with the material intimately bonded together on both sides thereof about the wires of the strips; to control the individual twisting of the straight portion between loops of the strips and the deflection and contour produced in adjacent strips over an area in the load-supporting portion of a cushion by confining the central area of the supporting portion between layers of fabric material which are bonded together thereabout; and in general to provide a predetermined contour to a cushion made of zigzag spring strips by the application of fabric material to the strips which is simple in construction and economical of manufacture.

Other objects and features of novelty of the invention will be specifically pointed out, or will become apparent when referring for a better understanding of the invention to the following description taken in conjunction with the accompanying drawing, wherein:

Fig. 1 is a broken plan view of a spring cushion made of zigzag spring strips interconnected by layers of fabric material in a manner conforming to the present invention; and

Fig. 2 is an enlarged sectional view of the structure illustrated in Fig. 1, taken on the line 2—2 thereof.

The cushion construction herein illustrated follows that of the copending application of Nicholas Wolofski, Serial No. 55,633, filed October 20, 1948, and assigned to the assignee of the present invention. The springs 10 are made of wire bent back and forth to provide oppositely disposed adjacent loops 11 and 12 joined by straight portions 13. In the illustrated construction, a front end support is provided to the seating portion 14 of each spring strip by the V-shaped portion 15 extending downwardly therefrom. The rear end of each spring strip is bent to provide an arcuate downwardly and inwardly disposed portion 16, the lower end of which is attached to a base spring 17 of suitable construction. The front end of the V portion 15 in like manner is supported on the frame 17.

The frame 17 herein illustrated is made of wire, but it is understood that the frame may be made

of tubular elements, wood, and the like commonly employed in the art. A border wire 18 surrounds the seating portion at the front, sides and rear end and is retained in position by suitable clips 19. A listing strip of fabric material 21 is connected between the seating portion 14 of the spring strips and the top arm of the V portion 15 by rings 24 for producing a predetermined contour to the seating portion 14 and controlling the movement of the strips when the cushion is occupied and the automotive vehicle is driven over rough terrain.

When a load is applied to the seating portion 14 of the spring strips, they are deflected an amount conforming to the distribution of the load which is spread over the adjacent strips. Any deflection to the elements of the strip is accompanied by torsional strains in the straight portion 13 of the strip and by the spreading or contracting of the loops in the strips. The layers of fabric materials 22 and 23 control the tension on the strips and the deflection of the individual loops in the loaded area of the seating surface. The material being securely bonded together causes all of the strips to react to the load across the transverse dimension of the seating area an amount proportional to the distance of the strips from the point of application of the load taken in consideration with the amount of load applied.

One method which was utilized for attaching the fabric layers 22 and 23 to the top and bottom of the seating portion was to place a layer of fabric material 22 upon a flat or contoured surface and apply a suitable adhesive to the upper surface thereof. The spring unit after assembly is then placed upon the layer of fabric material 22 against the adhesive on the surface thereof and a second layer of fabric material 23 is then placed upon the inner or upper surface of the spring strips and adhered to the fabric layer 22 there beneath. A force-applying device, such as a pad or roller or the like is applied to the fabric material 23 to bond the two layers intimately to each other about the wire of the loops and straight portions of the strips and in the spaces between the strips. The ends of the material 22 and 23 are preferably secured to each other about the border wire at the sides of the seating area or one layer may be lapped over the border wire onto the other layer and adhered thereto.

What is claimed is:

1. In a spring unit for a cushion, a plurality of zigzag spring strips forming a seating area, a border wire extending around said seating area, means for securing the border wire to the seating area at the front and back thereof, a top and bottom layer of fabric material extending across the transverse dimension of said seating area in-

wardly a substantial distance from the front and rear edges thereof at the central main load-supporting portion of the area leaving a substantial portion of the front and rear ends of the strips unconfined, adhesive material securing said layers of fabric material to each other in unit relation at all points between the convolutions of the spring strips and the areas between the strips, and means for securing the ends of said fabric material to the border wire at the sides of the seating portion of the cushion.

2. In a spring unit for a cushion, a plurality of zigzag spring strips having a top seating area, a V-shaped supporting portion at the front and an inwardly deflected supporting portion at the rear, a frame to which a plurality of strips are secured to provide a resiliently supported seating area, a border wire extending around said area at the front and sides thereof and secured thereto, a listing strip joining the V-shaped supporting portions of the strips to the seating area inwardly from the front edge thereof, a top and bottom layer of fabric material for the central portion of said seating area inwardly of the point of connection with the listing strip, therewith, adhesive material for securing said fabrics in intimate relation about the wire of said zigzag spring strips and the areas therebetween for uniting said strips at the main load-supporting portion of the seating area, and means for securing the edges of said fabric material to each other about said border wire at the sides of said seating area.

3. The method of uniting a plurality of zigzag spring strips forming the body supporting portion of a seat, and having a border wire secured thereto, said method including the steps of applying a first strip of fabric material to said plurality in position to overlie the top thereof in an area inwardly of the front and rear edges of said plurality, applying a second strip to said plurality in position to underlie the first mentioned strip and the portion of said plurality covered by the first mentioned strip, bonding the layers together in intimate relation between the convolutions of the wires of said plurality and securing the ends of the fabric material at each side of the plurality to each other and about the border wire at the side of the frame.
